(57) **CLAIM**

The ornamental design for the marble lamp, as shown and described.

DESCRIPTION

FIG. 1 is a top plan view of a square embodiment of a marble lamp showing my new design;

FIG. 2 is a bottom plan view thereof;

FIG. 3 is a side elevation view thereof, all four sides being identical;

FIG. 4 is a cross-section view thereof taken along a line indicated on FIG. 1;

FIG. 5 is a side elevation view with the only difference from the embodiment portrayed in FIG. 3 being an unclaimed height;

FIG. 6 is a top plan view of a round embodiment of a marble lamp;

FIG. 7 is a bottom plan view thereof;

FIG. 8 is a side elevation view thereof, all side views being identical;

FIG. 9 is a cross-section view thereof taken along a line indicated on FIG. 6; and,

FIG. 10 is a side elevation view with the only difference from the embodiment portrayed in FIG. 3 being an unclaimed height.

Broken lines have been used to show environment and form no part of the claimed design.
